UNITED STATES PATENT OFFICE.

HARRY M. SPENCER, OF DUNMORE, PENNSYLVANIA.

SPARK-PLUG.

1,077,960.

Specification of Letters Patent.

Patented Nov. 4, 1913.

Application filed October 8, 1912. Serial No. 724,591.

To all whom it may concern:

Be it known that I, HARRY M. SPENCER, a citizen of the United States, residing at Dunmore, in the county of Lackawanna and State 5 of Pennsylvania, have invented a new and useful Spark-Plug, of which the following is a specification.

The present invention relates to improvements in spark plugs:

10 The primary object of this invention is the provision of a novel form of spark plug, in which the air gap between the relative sparking elements at the lower end of the plug is sealed by an insulating member, said insulating member being so disposed as to expose a plurality of sparking terminals upon the stationary member so that the coaction therewith of a plurality of rotatably mounted 15 sparking terminals of the opposed member 20 will be disposed in adjustable relation to the stationary sparking terminals and so that when the rotary members are rotated, the exposed surfaces of the stationary sparking terminals and insulating member may be 25 scraped, thus cleaning the accumulated carbon therefrom without the necessity of removing the plug from the cylinder.

A further object of the present invention is the provision in a spark plug of a stationary 30 electric element provided with a plurality of concentrically disposed sparking terminals in combination with a rotatably mounted stem carrying a plurality of sparking terminals, said terminals being in co- 35 active relation both for adjusting and cleaning relatively to the stationary terminals and being guided in its movement during rotation by an insulating member disposed to fill the air gap between the concentrically 40 disposed terminals and the insulating body carrying the stem, the rotation of the stem and terminals carried thereby cleaning simultaneously both the exposed portion of the stationary terminals and the insulation.

45 With the foregoing and other objects in view which will appear as the description proceeds, the invention resides in the combination and arrangement of parts and in the details of construction hereinafter described and claimed it being understood that changes in the precise embodiment of the invention herein disclosed can be made within the scope of what is claimed without departing from the spirit of the invention.

50 In the drawings—Figure 1 is a side elevation of the complete plug in operable posi-

tion. Fig. 2 is a vertical central sectional view therethrough. Fig. 3 is a bottom plan view of the plug as illustrated in Fig. 1. Fig. 4 is a perspective view of the lower end 60 of the rotary terminal carrying member. Fig. 5 is a detail perspective view of the insulating member disposed in the lower end of the plug.

Referring to the drawings, the numeral 1 65 designates the metal bushing which is provided with the threaded portion 2 for engagement with the plug socket of an explosive engine, the lower end of which is provided with a plurality of tapered sparking 70 terminals 3, preferably four in number, the lower edges of which at the spark gap portion being inclined as at 4, the purpose of which will presently appear.

Mounted within the bushing 1 is a sleeve 75 or tube of insulation 5 in whose bore 6 is disposed a metal casing or sleeve 7 having the enlarged socket or cavity 8 in the lower end thereof, while the lower end of the insulating bushing or sleeve 5 is reduced as at 80 9 to produce a concentric cavity 10 between the adjacent face thereof and the inner wall of the bushing 1. In most spark plugs, this space forms an air gap and is not sealed, and it has been found advantageous to seal 85 the space and form a continuation upon the lower end of the sleeve 5, this being accomplished by the insulating member 12, whose ring 11 is disposed to fit about and incase the lower end of the sleeve 5, as clearly 90 shown in Fig. 2 and fill the space therebelow and adjacent to and between the sparking terminals 3, the lower end of the insulating member 12 being provided with the convoluted portions 13 and 14 which form a guiding means for the rotary sparking terminals 19, as will presently appear. This insulating member 12 is composed of lava or other 95 insulating substance that will withstand the intense heat produced at the igniting end of the spark plug and within the explosive chamber and is properly cemented within the bushing 1 and upon the lower end of the insulating sleeve 5, the same being insertible from below and held to a certain extent in 100 place, by means of the flanged rim 7' of the sleeve or metal bushing 7.

The lock nut cap 15 is disposed for rotation upon the insulator 5 and for engagement with the threads 16 of the bushing 1 110 to maintain the parts in their relative locked positions.

- Disposed for rotation within the bore of the bushing 7 is a stem 17, upon whose lower end is mounted or carried, the enlarged cylindrical portion 18 fitted for sliding and 5 rotary movement within the socket 8 of the sleeve 7, and carried upon the lower end of the cylindrical portion 18 and disposed to ride upon the convoluted portions 13 and 14 of the insulating member 12 and 10 being disposed in sparking relation to the sparking terminal portions 4 of the stationary terminals 3, are the sparking terminals or arms 20, each one of which is provided with the inclined face 19 disposed for coaction with the inclined face 4 of its respective terminal 3. By this means, the terminals 19 may be readily adjusted to secure the desired spark between the faces 4 and 20 and when it is desired to clean such faces 15 4 and 20 and also the lower face of the insulating member 12, of any accumulation of carbon thereupon, the stem 17 is rotated in the direction of the arrow Fig. 1 so that the upper edge of the respective 20 arms 19 will act as a cutting means and also as a scraper riding upon the long curved portion 13 between the respective terminals 3 and finally upon the shouldered portion 14 before finally engaging the inclined portion 4 of the respective terminals 3, the 25 spring 21 exerting a normal tension against the locking disk 22 to hold the terminals 19 upwardly against the insulating member 12 and the terminals 3 during the rotation of 30 the stem through the keyed milled disk 23 mounted upon the upper end of the stem 17. The disk 22 and lock nut or disk 24 constitute a binding post for holding the electric terminal 25 in position.
- 40 A locking cap 26 is placed upon the upper end of the insulating bushing or sleeve 5 and is provided with a socket 27 for assisting in maintaining the spring 21 in its necessary position.
- 45 From the foregoing description, taken in connection with the drawings it is evident with a spark plug constructed according to the present invention, that the terminals 19 may be adjusted to accomplish the best possible result without the necessity of the removal of the plug from the engine cylinder and that when it is necessary to clean the carbon from the under surface of the terminals 3 and the insulating member 12, that 50 the stem 17 may be rotated through the milled disk 23, and that the terminals 19 will act as a scraping or cutting means for such purpose. It is also evident that by means of the spring 21, the sparking terminals 19 will be maintained in engagement with the relative portions 13 of the insulating bushing or member 12 and in proper spaced and 55 sparking relation with the inclined surfaces 4 of the respective terminals 3, so that the 60 jarring of the engine will in no way disturb the adjustment.
- What is claimed is:
1. A spark plug, including a metal bushing provided upon its lower end with a sparking terminal, an insulating body sealing the lower end of the bushing and partially embracing the terminal to provide a single exposed face to the terminal, said exposed face being flush with the face of the insulating body, a stem mounted for rotation within the insulating body, a sparking terminal carried upon the lower end of the stem, and means for maintaining the stem and its terminal in adjusted relation with respect to the terminal of the bushing. 65
  2. A spark plug, including a metal bushing having a plurality of sparking terminals, an insulating sleeve mounted in the bushing and terminating within and out of contact with the lower end of the bushing, a body of insulation fitted in the lower end of the bushing and about the lower end of the insulating sleeve, the lower face of said body being below the bushing and partially surrounding the terminals, whose sparking 70 faces are exposed through the body of insulation, and a plurality of rotatable sparking terminals disposed in sparking relation to the exposed ends of the terminals of the bushing and forming a cleaning means for 75 the lower face of the insulation body and stationary terminals when rotated. 80
  3. A spark plug, including a metal bushing having a plurality of sparking terminals, an insulating sleeve mounted in the bushing and terminating within and out of contact with the lower end of the bushing, a body of insulation fitted within the lower end of the bushing and about the lower end of the insulating sleeve, the lower face of 85 said body being below the bushing and partially surrounding the terminals, whose sparking faces are exposed through the body of insulation, a stem rotatably mounted within the insulating sleeve and operable 90 from the upper end thereof, and a plurality of sparking terminals carried upon the lower end of said stem for coaction with the exposed faces of the terminals of the bushing, said stem carried terminals when rotated 95 scraping the lower surface of the body of insulation and exposed ends of the terminals of the bushing to clean the same. 100
  4. A spark plug, including a metal bushing having a plurality of sparking terminals, an insulating sleeve mounted in the bushing and terminating within and out of contact with the lower end of the bushing, a body of insulation fitted in the lower end of the bushing and about the lower end of the insulating sleeve, the lower face of said body being below the bushing and partially surrounding the terminals, whose 105

- sparking faces are exposed through the body of insulation, a plurality of rotatable sparking terminals disposed in sparking relation to the exposed ends of the terminals of the bushing and forming a cleaning means for the lower face of the insulation body and stationary terminals when rotated, and means for resiliently holding the rotary sparking terminals toward and in contact with the terminals of the bushing and insulating body when rotated and against the insulating body when stationary.
5. A spark plug, including a metal bushing having a plurality of sparking terminals, an insulating sleeve mounted in the bushing and terminating within and out of contact with the lower end of the bushing, a body of insulation fitted within the lower end of the bushing and about the lower end of the insulating sleeve, the lower face of said body being below the bushing and partially surrounding the terminals, whose sparking faces are exposed through the body of insulation, a stem rotatably mounted within the insulating sleeve and operable from the upper end thereof, a plurality of sparking terminals carried upon the lower end of said stem for coaction with the exposed faces of the terminals of the bushing, said stem carried terminals when rotated scraping the lower surface of the body of insulation and exposed ends of the terminals of the bushing to clean the same, and means for resiliently holding the rotary sparking terminal toward and in contact with the terminals of the bushing and insulating body when rotated and against the insulating body when stationary.
6. A spark plug, including a metal bushing having a plurality of sparking terminals projecting from the lower end thereof, each terminal being provided with an inclined sparking face upon the lower end thereof, an insulating body mounted in the bushing throughout the length thereof and partially incasing the lower end of the bushing and the adjacent portions of the sparking terminals, the inclined faces of the sparking terminals being exposed through the insulating body, a stem mounted for rotation within the insulating body, a plurality of sparking terminals carried upon the lower end of said stem one to each sparking terminal of the bushing, the sparking surfaces of said terminals being disposed at an incline parallel to the incline of the respective terminals of the bushing, and means for rotating said stem and terminals to clean the lower exposed faces of the insulating body and stationary terminals, and means for resiliently holding the stem and terminals toward the bushing and insulating body, said terminals of the stem being normally held against the insulating body and in sparking relation to the respective terminals of the bushing.
7. A spark plug, including a metal bushing having a plurality of sparking terminals projecting from the lower end thereof, each terminal being provided with an inclined sparking face upon the lower end thereof, an insulating body mounted in the bushing throughout the length thereof and partially incasing the lower end of the bushing and the adjacent portions of the sparking terminals, the inclined faces of the sparking terminals being exposed through the insulating body, a stem mounted for rotation within the insulating body, a plurality of sparking terminals carried upon the lower end of said stem, one to each sparking terminal of the bushing, the sparking surfaces of said terminals being disposed at an incline parallel to the incline of the respective terminals of the bushing, means for rotating 130
8. A spark plug, including a metal bushing having a plurality of sparking terminals projecting from the lower end thereof, each terminal being provided with an inclined sparking face upon the lower end thereof, an insulating body mounted in the bushing throughout the length thereof and partially incasing the lower end of the bushing and the adjacent portions of the sparking terminals, the inclined faces of the sparking terminals being exposed through the insulating body, a stem mounted for rotation within the insulating body, a plurality of sparking terminals carried upon the lower end of said stem one to each sparking terminal of the bushing, the sparking surfaces of said terminals being disposed at an incline parallel to the incline of the respective terminals of the bushing, means for rotating said stem and terminals to clean the lower exposed faces of the insulating body and stationary terminals, and means for resiliently holding the stem and terminals toward the bushing and insulating body, said terminals of the stem being normally held against the insulating body and in sparking relation to the respective terminals of the bushing.
9. A spark plug, including a metal bushing having a plurality of sparking terminals projecting from the lower end thereof, each terminal being provided with an inclined sparking face upon the lower end thereof, an insulating body mounted in the bushing throughout the length thereof and partially incasing the lower end of the bushing and the adjacent portions of the sparking terminals, the inclined faces of the sparking terminals being exposed through the insulating body, a stem mounted for rotation within the insulating body, a plurality of sparking terminals carried upon the lower end of said stem, one to each sparking terminal of the bushing, the sparking surfaces of said terminals being disposed at an incline parallel to the incline of the respective terminals of the bushing, means for rotating 130

said stem and terminals to clean the lower exposed faces of the insulating body and stationary terminals, and means for resiliently holding the stem and terminals toward the bushing and insulating body, the lower end of the insulating body between the respective terminals of the bushing being convoluted to form a guiding means for the terminals of the stem during the rotation thereof of when cleaning the insulating body and exposed faces of the stationary terminals.

10. A spark plug, including a metal bushing having a plurality of sparking terminals projecting from the lower end thereof, each terminal being provided with an inclined sparking face upon the lower end thereof, an insulating body mounted in the bushing throughout the length thereof and partially incasing the lower end of the bushing and 15 the adjacent portions of the sparking terminals, the inclined faces of the sparking terminals being exposed through the insulating body, a stem mounted for rotation within the insulating body, a plurality of 20 sparking terminals carried upon the lower end of said stem one to each sparking terminal of the bushing, the sparking surfaces of said terminals being disposed at an incline parallel to the incline of the respective terminals of the bushing, means for rotating said stem and terminals to clean the lower exposed faces of the insulating body and stationary terminals, and means for resiliently holding the stem and terminals 25 toward the bushing and insulating body, said terminals of the stem being normally held against the insulating body and in 30 sparking relation to the respective terminals of the bushing, the lower end of the 35 insulating body between the respective terminals of the bushing being convoluted to 40 form a guiding means for the terminals of

the stem during the rotation thereof when cleaning the insulating body and exposed faces of the stationary terminals.

45

11. A spark plug, including a metal bushing provided upon its lower end with a plurality of sparking terminals, an insulating body sealing the lower end of the bushing and partially incasing said terminals to provide a single exposed face to each terminal flush with the face of the insulating member, a stem mounted for rotation within the insulating member, a plurality of sparking 50 terminals carried upon the lower end thereof, one to each terminal of the bushing and means for maintaining the stem and its terminals in adjusted relation with the respective terminals of the bushing.

55

12. A spark plug, including a metal bushing provided upon its lower end with a plurality of sparking terminals, an insulating body sealing the lower end of the bushing and partially incasing said terminals to provide a single exposed face to each terminal 60 flush with the face of the insulating member, a stem mounted for rotation within the insulating member, a plurality of sparking terminals carried upon the lower end thereof, one to each terminal of the bushing, and 65 means for maintaining the stem and terminals in adjusted relation with the respective terminals of the bushing and for resiliently holding the stem and its terminals in relative position to the terminals of 70 the bushing and insulating body.

75

In testimony that I claim the foregoing as my own, I have hereto affixed my signature in the presence of two witnesses.

HARRY M. SPENCER.
